UNITED STATES PATENT OFFICE.

LOUIS F. KLIPSTEIN AND JOHN U. BARR, OF NEW ORLEANS, LOUISIANA.

MOP-WIRING MACHINE.

Application filed October 29, 1927. Serial No. 229,674.

This invention relates to a machine for wire binding mops and the like, and consists of an improvement on the mechanism disclosed by our pending application Serial No. 5 119,193, filed June 28, 1926, Patent No. 1,675,220, dated June 26, 1928.

The primary object of the present improvement is to provide a machine of the class specified embodying a series of instrumentalities for facilitating the securing of mop strands to a handle by means of a wire binder that is duplicated in its application, applied to the inner and outer portions of the mop head by a novel form of mechanism that is operable to reliably effect a performance of the several steps incident to the application of the wire binder and in the proper timed relation.

A further object of the invention is to provide mechanism for effecting a regular feed of the wire, forming the necessary hook means in the wire, slackening of the latter at proper intervals, guiding and cutting the wire to complete the operation without relying upon as extensive manual operation as in the structure embodied in our prior application heretofore noted and all controlled from a single power applying point, to effectively and more expeditiously complete the work and hold the 25 mop strands in secure engagement with the mop handle.

With these and other objects and advantages in view, the invention consists in the construction and arrangement of the several parts which will be more fully hereinafter described and claimed.

In the drawings:—

Figure 1 is a side elevation of a portion of a machine broken through in parts embodying 40 the improved features of the invention, portions of the mechanism also being shown in section and in full and dotted lines.

Figure 2 is a front elevation of the machine also broken through in part and broken away 45 to illustrate the improved mechanism, the operation in part being shown in full and dotted lines.

Figure 3 is an enlarged sectional side elevation particularly for controlling the operation of the clamping, cutting and bending attachments.

Figure 4 is an enlarged front side elevation of a part of the mechanism shown by Figure 3.

55 Figure 5 is a horizontal section on the line 5—5, Figure 3.

Figure 6 is an enlarged sectional view of a lower controlling cam wheel, worm wheel, clutches and intermittently related mechanism constituting the lower essential motion 60 controlling mechanism.

Figure 7 is a plan view partly in section and partly broken away, of the mechanism shown by Figure 6.

Figure 8 is a transverse section on the line 65 8—8, Figure 7.

Figure 9 is an enlarged sectional side elevation in full and dotted lines of portions of the cutting and bending mechanism.

Figure 10 is a horizontal section with a 70 part of the mechanism broken away and in section on line 10—10, Figure 11.

Figure 11 is a transverse vertical section through the cutting mechanism illustrating the bending mechanism thereunder in front 75 end elevation.

Figure 12 is a detail end elevation, on an enlarged scale, of the bender arm.

The numeral 5 designates a bed or table 80 of suitable dimensions having a slot 5^a extending rearwardly thereinto from the front edge and formed with an outer flaring entrance or diverged inlet 5^b. The bed or table 5 has supporting legs 6 connected by transverse braces, preferably constructed from channel iron of suitable dimensions, as at 7, and also formed with lower securing angle iron feet 7^a adapted to be secured to a support or the flooring on which the machine is mounted. Rising from the rear portion of 90 the bed or table 5 is a vertical frame comprising parallel spaced uprights 8 having bracket plates 9 secured to the front and rear sides thereof and provided with lower flanges 10 which are bolted or otherwise secured to the 95 bed or table 5. Extending forwardly from the vertical frame between the uprights 8 are upper, intermediate and lower horizontal supporting arms 11, 12, 13 and 13^a, each essentially comprising parallel plates or strips 100 11^a. A suitable wire guide is adapted to be applied on the upper end of the upright frame of a character similar to that disclosed by our aforesaid application, and through which a wire 16 is regularly fed downwardly 105 over the front portion of the machine from a suitable reel or other source of supply. The parallel plates or strips 11^a of the arms 11, 12 and 13 embrace and are terminally secured to an upright fixed guide shaft 17, 110 which has its upper end coinciding with the upper edges of the plates or strips 11^a of the

upper arm 12, and at its lower extremity terminates coincidentally with the lower edges of the plates 11^a of the lower arm 13. On the left sides of the arms 12 and 13 a 5 guide rod or strip 18 is secured, and thereon is adjustably mounted a check 19 and a trip 20, the said check and trip being held in their adjusted positions, respectively, by set screws 21 and 22 which bind against the rear side 10 edge of the guide rod or strip 18. The check 19 projects forwardly a predetermined distance and has a depending angular terminal 23, the lower edge 24 of said check being horizontally straight. The trip 20 has a projecting 15 slideable trip nose 25 mounted in the forward extremity thereof and provided with a downwardly and outwardly tapered face 26, for convenience in passing the same by a part of the mechanism elevated above the said 20 trip nose during the operation of the machine. The trip nose 25 has a pin 27 extending therethrough and engaging opposite slots 28 in the sides of the forwardly projecting extremity of said trip, a spring 8 being 25 mounted in rear of the trip nose 25 within the trip 20; as shown by Figure 1 in full and dotted lines, so as to always maintain the said trip nose in normal forwardly projected position and free for actuation by the mechanism 30 cooperating therewith.

A clamp is mounted to vertically move or slide on the upright fixed shaft 17 and operates between the lower arm 13 and the check 19, the said clamp consisting of a forwardly 35 projecting arm 29 having a slot or seat 30 extending through the outer free end thereof and communicating with a vertical bore 31 located at a distance inwardly from the outer end of said arm. Extending transversely 40 and horizontally through the outer end of the arm 29 is a shaft 32 having a cam or eccentric 33 fixed thereon and operating in the said slot or seat 30, the left hand end of the said shaft 32 projecting outwardly beyond 45 the adjacent side of the arm 29 and having a trip wheel 34^a fixed thereon and formed with radial arms 35 adapted to be struck by the trip nose 26 and the outer angularly depending end of the check 19. The cam 33 is 50 clearly shown in side elevation by Figure 3 and is free to operate within the slot or seat 30. Within the bore 31 clamping elements are mounted and consist of two semi-circular members 34 held in place by a lower securing device or tubular nut 34^a, the said members having grooves 36 in their inner opposing faces which are vertically straight. The clamping members 34 are shiftable, one 55 towards the other, within the bore 31, the upper part of the bore being reduced, as at 37, and in alignment with an upwardly projecting tube 38 secured at its lower end on the upper edge of the arm 29 and extending to 60 and through a projection or block 39 which is disposed above the arm 12 and has a bore 40

extending vertically through the outer extremity thereof for passage therethrough of the shaft 17, the upper end of the tube 38 being secured to the outer extremity of the said projection of the block 39. This projection or block 39 has its rear end fixed to the upper reduced extremity of a rack 41 with teeth 42 in its rear edge, the lower end of the said rack being secured to the rear end of the arm 29 of the clamping means. 75

Depending from the lower side of the outer end of the arm 17 is an angular guide foot 43, which is held in fixed position by securement to said arm and also to the arm 13^a immediately below, and in its horizontal member 43^a is formed a vertical guide bore 44 which is intersected by a horizontally disposed die block 45. Rising from the horizontal member 43^a of the foot 43 and in alignment with the bore 44 is a comparatively 80 short vertical guide tube 46 over which telescopes a tube 47 of slightly larger diameter and which, in turn, has a tube 48 telescoping thereover and associated with an upper tube 49 of still larger diameter 90 secured to the lower edge of the arm 29. The telescopic tubes 46, 47, 48 and 49 provide guide means for the wire 16 and are in alignment with the tube 38 projecting from the upper edge of the said arm 29 to the block 95 39 above. The tubular telescopic sections 46, 47, 48 and 49 are of such length and associated against separation in such manner that they will effectively operate to correspond to the 100 distance between the lower horizontal member 43^a of the foot 43 and the arm 49 without dissociation, the said tubular sections, when fully lowered or collapsed, causing the upper largest diametrical telescopic pipe section 49 to fully cover over the pipe sections 48, 47 and 105 46 below the said largest section. By means of these tubular guides the wire 16 is regularly fed downwardly without liability of becoming misplaced or entangled with the adjacent mechanism and with certainty as 110 to straight vertical feed of the same. The telescopic tubular sections just referred to as well as the tube 38 also align with the bores 31 and 41, respectively, formed in the clamp and the horizontal member 43^a of the lower angular guide foot 43, and furthermore the joints between the section 46 and the tubular sections 47, 48 and 49 are so formed that there will be no obstruction to the free downward movement of the wire 16 therethrough. 115

The die block 45 is mounted in the outer portion of a cutter bore 50 extending horizontally through the foot 43^a in rear of said die block, and reciprocatingly mounted in the bore 50 is a cutter 51 having its forward end reduced by equally tapering the upper and lower sides 52 thereof between guards 53 having front blunt ends 54 adapted to bear against the inner end of the die block 45 to prevent the cutting edge 55 of the cutter 51 120 125 130

from being crushed or dulled by forceful contact with the said rear edge of the block. The die block is removably held in the forward extremity of the bore 50 by a wedge 5 pin 56, as shown by Figure 9. The rear end of the cutter 51 is secured to a head 57, and between the front terminal of the head and the rear extremity of the member 43^a a spring 58 surrounds the rear extremity of the cutter 51 to assist in restoring the said cutter to its retracted position after it has been moved forwardly within the bore 50 in performing its cutting function. Secured to the opposite side portions of the head 57 longitudinally disposed parallel plungers 59 are secured and operate in grooves or ways 60 formed in the opposite sides of the said foot 43^a. The plungers 59 have front terminals inwardly and forwardly inclined faces 61, which are adapted to engage relatively shaped faces 62 at the rear terminals of the upper portions of oppositely positioned clamping dogs 63 fulcrumed, as at 64. These dogs are located in the lower portions of the opposite sides of the foot 43^a and have downwardly and inwardly projecting free extremities or clamping members 65 which are oppositely disposed ahead of and close to a fixed depending guide 66 projecting from the lower edge of the foot 43^a. This foot has a front vertical straight face 67 in alignment with the lower outlet of the bore 44. As shown by Figure 9, the opposing faces of the clamping members 65 are converged towards their lower extremities, as at 68. The upper extremities of the clamping dogs 68 have inwardly reduced extensions 69 which project into the grooves or ways 60 when operated by the plungers 59, as indicated in Figure 11. The head 57 is connected to the lower arm of a bell crank 70 which is fulcrumed, as at 71, between the parts of the lower arm 13^a, the upper rearwardly projecting arm of the bell crank lever carrying a roller 72 in line with and adapted to engage the lower upwardly and forwardly inclined contact face 73 or a sliding carrier 74, all as clearly shown by Figure 3, and disposed between parts of the arms 13 and 13^a. This carrier 74 is of block-like form, and has a slot 75 formed therein of predetermined contour, and is also formed with opposite elliptical slots 76 in the sides thereof through which extends a shaft 77 and also through a cam 78 disposed in the said slot 75 and having a contact cam projection 79 which engages a roller 79^a in advance thereof in the carrier 74. In the rear end of the carrier 74 a roller 80 is mounted for engagement with the lower reduced end 81 of a manually operative lever 82 fulcrumed, as at 83, between the uprights 8 of the frame and the lower parts 13 and 13^a, the said manually operative levers 82 extending also upwardly through a forwardly projecting movement restricting strap 84 and

having at its upper end a suitable handle or grip means 85 for operating the same. It will be understood, therefore, that the forward reciprocating movement of the cutter 51 is against the resistance of the spring 58, and when forward reciprocating pressure is relieved from the head 57, the said spring operates as a retractive means, as heretofore indicated. The shaft 77 extends into suitable opposed bearings 86, as shown by Figure 5, and has on one end an operating gear 87 held in continual mesh with an idler 88 on a shaft 89 having bearing in the arm 13, the said idler 88, in turn, meshing with a drive gear 90 on a shaft 91 which is mounted in a rear extension frame secured to and supported by the uprights 8 and comprising front and rear plates 92 and 93 of the shape shown in the drawings.

On the end of the shaft 91 outside of the gear 90 is a pear-shaped carrier 94 having an inwardly projecting pin 95, as clearly shown by Figure 4, to cooperate with a Geneva wheel 96 provided with radial slots 96^a, having the usual operation and being mounted on a shaft 97. The shaft 91 extends entirely through the plates 92 and 93 of the extension frame, and on its end opposite that to which is applied the gear 90 and carrier 94, and fixed and exterior of the plate 93, is a beveled gear 98 keyed thereon and held in continual mesh with a corresponding beveled gear 99 on the upper end of the forwardly inclined shaft 100 mounted in a suitable bearing, at its upper extremity, as at 101. The shaft 97, on the end thereof opposite that having the Geneva wheel 96, has a spur gear 102 fixed thereon and exterior of the plate 94 above the beveled gear 98, which meshes with a motion transmitting pinion 103 on a shaft 104, the latter also having a spur gear 105 fixed thereon and meshing with a pinion 106 on the adjacent end of a shaft 107 extending through and bearing in the two plates 93 and 92. It will, therefore, be understood that the shaft 91 is driven from the beveled pinion 98 operated by the pinion 99 on the upper end of the shaft 100, and through the pin 95 the carrier 94 operates at regular intervals the Geneva wheel 96 to rotate the shaft 97, the latter shaft, in turn, similarly operating a gear 102 at intervals and also mounted on the extremity of the shaft 97 opposite that carrying the Geneva wheel 96, the said gear 102 meshing with a pinion 103 on a shaft 104 and the latter, in turn, operating the gear 105 which actuates the pinion 106 on the shaft 107. In other words, the spur gear 102, pinion 103, and spur gear 105 are motion transmitting gears, proportioned or dimensioned in accordance with the predetermined time of operation, whereby the pinion 106 and shaft 107 will be rotated at a proper rapidity of intermittent motion through the actuation of the Geneva wheel 100.

96 by means heretofore fully explained. The shaft 107 has fixed thereon between the plates 92 and 93 a cam 108 as shown by Figure 3, and on the shaft 91 between the plates 92 and 93 is an oscillating lever 109 having an intermediate rearward projection 110 terminally carrying a roller 111 which continually bears against the periphery of the cam 108. The lower end of the lever 109 is movably attached 10 to the rear end of a link 112, the forward end of said link being, in like manner, movably attached to the rear end of a rod 113 that is terminally fixed at its forward extremity in a nut 114 with an upper bifurcation 115, as 15 also clearly shown by Figure 3. The nut 114 is secured to a longitudinally reciprocating bender shaft 116 having a front reduced extremity 117 disposed in straight horizontal position under the cutting mechanism heretofore explained. In the upper portion of the nut 114 a screw 118 is mounted and has an inner reduced end 119 projecting into a helical groove 120 formed in the shaft 116 and operating to produce a half turn of the latter shaft and its forwardly extending extremity 117. The forward reduced extremity 117 of the shaft 116 is mounted and moves in a bearing 121 having a pedestal support 122 rising from the bed 5 and is free to longitudinally reciprocate as well as rotate in the bearing 121. A rod 123 is also associated with the reduced extremity 117 of the shaft 116, and has a front terminal also mounted to reciprocate in an upper extension of the bearing 121, the rod 123 being provided with a rear depending bearing coupling 124 through which the forward reduced extremity 117 of the shaft 116 extends and is free to rotate, the said bearing 124 being applied at the shoulder 125 formed at the intersection of the shaft 116 and the reduced extremity 117. The forward extremity of the rod 123 has a deflected guide 126 attached to and movable therewith, and arranged close to, but spaced apart from the forward terminal of the reduced extremity 117 of the shaft 116, the said forward reduced extremity 117 and guide 126 unitedly forming the means for providing the bender for operating upon the wire which depends from the cutting mechanism above. From the rear extremity of the shaft 116 a rod 127 extends to and terminates in a rear angular tilting balance attachment 128 secured thereto, both the rod 127 and the rod 113 moving in a bearing and stop 129 held by the frame and also through the lower portion of the upright structure of the frame. A bar 130 also projects from the rear side of the frame upright and has its rear extremity 131 directly under the balance attachment 128 to insure the maintenance of the latter in straight or normal position and constant normal vertical position of the slot 132 between the reduced extremity 117 and guide 126 in the event that the screw 118 becomes worn

and loosens. The forward reduced extremity 117 of the shaft 116 has a slot 132 formed therein; the said slot being offset to permit the wire to easily leave the bender, as clearly shown by Figures 11 and 12.

70

The movement of the bender mechanism is controlled, as will be understood, by the operation of the cam 108. When the roller 111 is at the point L of the cam, the bender shaft 116 with its reduced extremity and the guide 126 cooperating therewith will be projected forwardly under the cutting mechanism heretofore described, and when the said cam 108 has been operated so that the roller 111 will occupy the position between the points L and M, the wire is fed through the guide 126, as shown by Figure 11, the guide having a yielding movement and the wire being fed from the latter into the slot of the bender extremity. When the cam is engaged by the roller 111 between the points M and N, the nut 114 and the screw 118 with its reduced terminal 119 acts in the helical groove 120 of the bender shaft 116, and said nut at this time will be in engagement with the bearing 121, 90 a half turn being imparted to the bender shaft and the loop or terminal hook formed on the wire. From the points N to O of the cam, when the latter is engaged by the roller 111, the bender shaft 116 with its reduced extremity 117 is permitted to resume normal retracted position by the operation of the balancing attachment 128 and the spring cooperating therewith. The bender shaft 116 with its reduced extremity 117 is prevented from rotating, or to the extent of a half turn as indicated, until the said shaft is in contact with the bearing 121, and the balancing attachment 128 functions only to restore the shaft 116 with its reduced extremity 117 when the position of the cam 108 and roller 111 permits unrestricted operation of the said balancing attachment. The bearing 124 is in the form of a grooved collar, and the rod 123 that extends forwardly therefrom has a depending pin 123' at its rear end which loosely depends into the said grooved collar forming the bearing 124, so that when the shaft 116 with its extension 117 is turned there will be no restriction to said movement, and the said rod 123 will also be maintained in a proper operating position.

95

105

110

115

120

125

130

The main driving mechanism for the several mechanisms heretofore described is located in the base structure of the machine below the table 5 and comprises a transverse main shaft 132 having suitable pulleys 133 which will be equipped with any well known form of belt shifting attachment, the said shaft 132 being located at the rear end of the base structure and supported in suitable bearings 134, and having a worm 135 which is held in continual mesh with a worm wheel 136 on the rear end of a countershaft 137. This countershaft 137 extends forwardly

130

under the table 5 towards the front of the base structure, and has fixed on its front end a cam disc 138 in which is formed a cam groove 139 of substantially heart-shaped 5 form eccentrically disposed in the front face of the said cam disc, as clearly shown by Figures 2, 6 and 7. The shaft 137 is also mounted in suitable bearings, and movable transversely across the face of the cam disc 138 is a 10 horizontally disposed rack bar 140 having teeth 141 which are held in mesh with the pinion 142 at the lower end of a vertical shaft 143 extending forwardly through a suitable bearing 144 in the table 5 and an upper terminal bearing 145. Secured to the arm 12 and fixed to the upper extremity of said shaft 15 is a beveled pinion 146 meshing with a corresponding beveled pinion 147 on a short horizontal shaft 148, (see Figures 1 and 2,) carrying 20 a pinion 149 held in mesh with the rack bar 41 secured at its lower end to the rear end of the arm 29 of the clamping means and at its upper end to the projection or block 39. Through the medium of this mechanism, the 25 rack bar 41 and parts heretofore described moving therewith are vertically reciprocated in timed relation at intervals through the actuation of the said lower rack bar 140 mounted in suitable bearings 150 in various parts of the frame, and secured to the said rack bar 140 by a screw 151 is a cam roller 152 which 30 engages and travels in the cam groove 139 of the cam disc 138, as clearly shown by Figure 7. The rack bar 140 is reciprocated longitudinally in opposite directions by the action of the cam groove 139 relatively to the roller 152. The shaft 132 continues to run during the operation of the machine and is thrown into and out of driving connection 40 with relation to the shaft 137 by suitable clutch mechanism which, in the present instance, consists of a main clutch head 153 shiftably secured to the shaft 137 to rotate with the latter by a spline and groove construction 154, disposed for engagement with a corresponding clutch member 155 associated with the hub of the worm wheel 136. The clutch head 153 and the clutch member 155 are correspondingly toothed, as at 156, 45 so as to interlock, and the clutch head has mounted thereon a roller 157 to engage a cam groove 158 of a clutch shifting lever 159 hinged at one end, as at 160, to the base structure of the frame as shown by Figure 7. The clutch head 153 is engaged by a tension spring 161 surrounding the shaft 137 adjusted through the medium of a collar 162a adjustably mounted on the shaft 137, so that the 50 said clutch head will be shifted, when free from control, by the cam groove 158 of the lever 159 and the engagement of the roller 157 with said cam groove. The disengagement of the clutch head 153 relatively to the clutch member 155 ensues when the roller 157 55 is located in an arcuate recess 162 of the cam

groove 158 of the lever 159, as shown by dotted lines in Figure 7, and as long as the lever 159 is lowered, the retraction of the clutch head 153 or disengagement from the clutch member 155 will remain constant as long as 70 the roller 157 is located in the arcuate recess 162 of the said lever. Due to the cooperative engagement of the lever 159 with the clutch head 153 the shaft 137 will be rotatively inert, the said shaft 137 only being actuated when 75 the clutch head 153 is in engagement with the clutch member 155 of the worm wheel 136. The worm wheel 136 is held in fixed position relatively to the shaft 137 by opposing collars 163 and 164 engaging the same in the central portion, as shown by Figure 6, so that the worm wheel 136 will be constantly in a location for instantly transmitting motion from the shaft 132 through the medium of the worm 135. 80

The shaft 137 is held by the bearings 165 and 166, adjacent to which latter bearing is a beveled gear 167. Between the same and the bearing 166 is a thrust 168 secured to said shaft, the beveled gear 167 continually meshing with the beveled gear 169 on the lower end of the shaft 100 by means of which motion of the said shaft 137 is transmitted to the mechanism for operating the bender and intermittently related to the actuation of the cutting mechanism through the operation of the shaft 89, idle gear 88, driving gear 90 and the shaft 91. Incidentally, the lever 109 fixed to the shaft 91 has a rod 170 secured thereto and to its upper free end is attached the lower end of a spring 171 which, in turn, is connected to the uprights of the frame work rising from the bed 5. By means of rod 170 and spring 171, the said lever 109 is caused to have a tendency to return to its normal position, the cam 108 acting on the roller 103 against the resistance of the spring 171 attached to the rod 170 and by means of which a tendency to quick motion towards its normal position is at all times imparted to the 105 said lever 109, the link 112, the rod 113 and the nut 114 slidably mounted on the shaft 116. 110

The clutch mechanism including the clutch head 153 and member 155 are controlled as to their operation to transmit motion from the worm wheel 136 to the shaft 137 and by means of the latter to the remaining mechanism, as heretofore explained, through the operation of a foot treadle 172 fulcrumed at an intermediate point to the lower portion of the base structure, as at 173, and the front end of this treadle is depressed against the resistance of a spring 174 attached thereto and to a part of the base structure of the frame above. To the normally elevated front end of the treadle 172 a rod 175 is secured extending upwardly and being connected to the lever 159, and by means of which the latter is depressed to effect engagement between the said latter lever and the roller 157 to control the opera- 120 125 130

tion of the clutch head 153 in the manner also heretofore explained. The pedal 172 is readily accessible at the front portion of the base structure of the machine during the several operations of applying the binder wire to the mop head and at proper intervals which will be determined by the operator.

Preliminarily, the wire 16 is fed to the machine or passed downwardly through the bore 40 of the block 39 and the tube 38, and also through the bore 31 in which are located the clamping members 34, the outermost clamping member being of harder material than the remaining similar member, and being adapted to clamp against the wire 16, the said wire passing downwardly from the clamping member through the telescopic tube sections 49, 48 and 47 and the tube 46. The wire 16 is then continued through the bore 44 between the forward reduced extremity of the cutter 51 and die block 45 and thence downwardly through the slot 5^a opening out through the front of the table 5. A hook 16^a is first normally formed on the lower end of the nose 16 when the said wire is fed downwardly through the table 5, the bending mechanism remaining without operation at such time, and the mop head is then applied to the handle and placed on said table 5, the wire being looped around the inner portions of the said head, or around a certain quantity of the mop strands, and the hook 16^a being caught over the portion of the wire 16 above. At this time, the wire is drawn upwardly to tighten the loop formed by the wire around the mop strands and to bring the hook engaged portion of the wire close to the underside of the cutter, said upward drawing of the wire being accomplished through the clamping means comprising the members 34 held within the bore 31 of the arm 29, the cam or eccentric 33 bearing against the outer member 34, the trip wheel 34^a, which is adapted to contact with the trip nose 25 of the trip 20, loosening the clamping action of the clamp sufficiently to permit the latter to slide upwardly until it engages with the depending angular terminal 23 of the check 19, which rotates the cam 32 through the trip wheel 33 to again tightly engage the wire 16 and exert sufficient tension on the latter to exert a securing effect relatively to a portion of the wire applied around the mop strands and a portion of the handle therein, and at the same time pull the partially secured mop head upwardly close to the underside of the cutting mechanism.

The arm 29 and the block 39 are connected to opposite extremities of the rack 41 and move as a unit on the shaft 17, and the guide rod or strip 18 remains fixed so that the trip 20 with its nose 25 and the check 19 may operate, as just explained, to release the one clamping member 34 with relation to the other clamping member, and subsequently re-

secure the wire 16 therein by a tightening operation through the cam 33 on the shaft 32, to again hold the said wire in secured position in the clamping mechanism at the proper timed interval. The unit is reciprocated by the shaft 143 and the pinion 142 which is operated by the rack bar 140 through the medium of the roller 152 engaging the cam groove 139 of the cam disc 138. The shaft 143 is rotated two cycles during one revolution of the said disc 138 owing to the shifting position of the roller 152 in the cam groove 139 and the length of movement imparted to the rack. During the movement of the wire downwardly through the mechanism, as heretofore explained, the latter is prevented from bending or becoming displaced, and at a proper interval the cutting and bending mechanism are brought into play and complete a second hook on the severed end of the wire 16 formed at an angle to the hook 16^a, being also passed around the main body of the wire close to the hook 16^a and drawn closely towards the latter. When this first or preliminary securing is accomplished, the mop head and handle are removed and then replaced with the outer mop strands thrown over the inner secured ones and the same operation of wiring is employed relatively to the outer side of the mop head, so that the said head will be firmly attached to the handle by a double wiring.

What is claimed as new is:

1. In a machine for wire binding mops and the like, a work table, wire feeding and clamping means, wire cutting means, bending and guiding means including a forwardly and rearwardly slidable and rotatable spindle having a front slotted end also provided with a wire opening therethrough and a yieldable guide, and mechanism for operating the said instrumentalities.

2. A machine of the class specified, comprising a work table having a slot opening out through the front portion thereof, an upright frame held on the table and provided with supporting means disposed in spaced relation, wire feeding and clamping means vertically movable with relation to the upright and including a guide tube held on the clamping means and extending through the guide means, collapsible tubular feeding means below said clamping means, a wire cutting means below the clamping means and also supporting a wire guiding tube, bending mechanism below the wire cutting mechanism having the main bending element thereof longitudinally shiftable forwardly and rearwardly and also rotatable and having a wire bending structure at its forward extremity and also having a guide associated therewith and separated therefrom, and mechanism for operating the several instrumentalities.

3. In a machine for wire binding mops and the like, a work table, wire feeding and clamp-

- ing means, wire cutting means, bending means including a forwardly and rearwardly slideable and rotatable spindle having a front slotted end and an opening therethrough and a 5 guiding means, means cooperating with the said spindle and guiding means to restore the latter to normal position, and mechanism for operating the said instrumentalities.
4. In a machine for wire binding mops and 10 the like, a work table, wire feeding and clamping means connected for unitary movement, wire cutting means below the feeding and clamping means, bending means below the cutting means and including a forwardly and 15 rearwardly slideable and rotatable spindle having a front extremity constructed to receive and bend a wire into a hook shape, and also provided with a guide, means cooperating with said spindle and guide to shift the 20 same and also impart a rotating movement to the spindle, balancing means connected to the rear end of the spindle for restoring it to normal position, and mechanism for operating the said instrumentalities.
- 25 5. A machine of the class specified, comprising wire feeding means, wire clamping means connected to and spaced from a part of the wire feeding means and having an exteriorly located operating device, vertically 30 adjustable trip and check devices for engagement with the exteriorly located operating device of the clamping means, wire cutting means below the clamping means, wire bending and guiding means below the cutting 35 means, and mechanism for operating the several instrumentalities.
6. In a machine for wire binding mops and the like, a work table, an upright frame held by the table and including supporting means, 40 wire feeding and clamping means in superposed spaced relation and connected for uniform vertical movement, means for connecting the feeding and clamping means for unitary reciprocating movement, wire cutting means below the feeding and clamping means, a horizontally shiftable bending and guide mechanism below the wire cutting means, a drive shaft journalled in the work table, a cam mounted upon the drive shaft, a rack 45 mounted for reciprocation in the work table and operably connected to be reciprocated by the cam, a vertical shaft provided with a gear for engagement with the rack, means for connecting said shaft to reciprocate the wire feeding and clamping means, and independent means operably connecting the wire cutting and bending means simultaneously with the operation of the cam.
- 50 7. In a machine for wire binding mops and the like, a work table, an upright frame held by the table and including supporting means, spaced wire feeding and clamping means having uniform vertical movement, a rack connecting said feeding and clamping means, wire cutting means having a guide bore there- 55
- through and also provided with a sliding cutter in part movable across the said bore, a shiftable bending and guide mechanism below the wire cutting means, a drive shaft journalled in the work table, a cam mounted upon the drive shaft, a rack mounted for reciprocation in the work table and operably connected to be reciprocated by the cam, a vertical shaft provided with a gear for engagement with the rack, means for connecting said shaft to reciprocate the wire feeding and clamping means, and independent means operably connecting the wire cutting and bending means simultaneously with the operation of the cam.
8. A machine for wire binding mops and the like, comprising a work table having wire-engaging elements disposed in vertical sequence thereover and consisting of wire feeding and clamping means and wire cutting 80 and bending and associated guiding instrumentalities, the wire feeding and clamping means being uniformly vertically movable and the wire cutting and bending instrumentalities held in fixed position relatively to the 85 said feeding and clamping means, a rack connecting the wire feeding and clamping means, a drive shaft journalled in the work table, a cam mounted upon the drive shaft, a rack mounted for reciprocation in the work table 90 and operably connected to be reciprocated by the cam, a vertical shaft provided with a gear for engagement with the rack, means for connecting said shaft to reciprocate the wire feeding and clamping means, and independent means operably connecting the wire 95 cutting and bending means simultaneously with the operation of the cam.
9. A machine for wire binding mops and the like, comprising a work table, wire feeding and clamping means disposed in spaced relation, a rack connecting said feeding and clamping means for unitary movement, wire cutting and slotted bending and guiding means below the feeding and clamping means, a drive shaft journalled in the work table, a cam mounted upon the drive shaft, a rack 100 mounted for reciprocation in the work table and operably connected to be reciprocated by the cam, a vertical shaft provided with a gear for engagement with the rack, means for connecting said shaft to reciprocate the wire feeding and clamping means, and independent means operably connecting the wire cutting and bending means simultaneously with the 105 operation of the cam.
10. In a machine for wire binding mops and the like, a work table, wire feeding and clamping means, wire cutting means, bending means including a forwardly and rearwardly slideable and rotatable spindle having a front slotted end, a drive shaft journalled in the work table, a reciprocatory rack bar mounted in the work table and operably connected to the drive shaft, a vertical shaft op- 110

- 130

erably connected to said rack bar and to the wire feeding and clamping means to impart reciprocation thereto, and gearing connecting the wire cutting and bending means to the drive shaft.

11. A machine of the class specified comprising a main frame, a drive shaft journaled therein, a cam mounted on said drive shaft, a rack bar mounted in the main frame and operably connected to said cam shaft to be reciprocated as the shaft rotates, a vertically movable frame mounted in the main frame, a vertical shaft for operably connecting said frame to the rack bar whereby as the 10 rack bar is reciprocated, the shaft is oscillated and the vertically movable frame is reciprocated, a wire clamp carried by said reciprocatory frame, means in the path to release the clamp as said frame is moved a predetermined distance upwardly, means in the path of the clamp and above said last means to operate the clamp to clamping position and to measure the length of wire to form the succeeding loop as the movable 20 frame continues upwardly, means operably connected to the main shaft for forming a

hook upon the lower end of the wire, and a cutter for the length of wire operably connected to the main shaft and operated to sever the length of wire.

30

12. A machine of the class specified comprising a main frame, a reciprocatory frame mounted thereon, a guiding clamp carried by the reciprocatory frame, means for operating the clamp to release or grip the wire, two adjustably mounted and spaced projections carried by the main frame and in the path of the clamp operating means to cause the clamp to be released after the frame has ascended a predetermined distance and to be caused to grip the wire to feed the wire by a downward movement and to pull the wire at the beginning of the up stroke and previous to the release thereof, and a telescopic guide below the clamp to be collapsed as the clamp descends and to be extended as the clamp ascends.
